AUTOMATIC STOP FOR NARROW FABRIC LOOMS

Alfred W. Heym, 1742 Starr St., Brooklyn, N.Y.

Filed Aug. 22, 1958, Ser. No. 756,610

11 Claims. (Cl. 139—371)

It has long been found difficult to provide a stop motion which will satisfactorily fulfill the practical requirements for looms of the narrow fabric type. Such looms conventionally involve a large number of shuttles located side by side across the width of the loom and serving respectively a large number of narrow fabric strips being simultaneously woven, the shuttles being slidably mounted between so called shuttle blocks and moved back and forth transversely of the fabric strips being woven, and the shuttle blocks being in turn carried by so called batten members which cause the shuttles to move back and forth longitudinally of the strips being woven, at the limits of the transverse reciprocatory movements above referred to. It is important on the one hand that such a stop motion be reliable in stopping the loom whenever the tension in the yarn being fed from any one of the shuttles falls to zero (for example when the yarn breaks or runs out) or whenever the tension falls below the range obtaining in normal production of satisfactorily woven products. It should be insured that the device will remain inactive even though the normal tension on the yarn be very slight, and yet be positive and reliable in stopping the machine when required. On the other hand the tension on the yarn varies substantially under different normal operating conditions and it is also important that the device be not oversensitive or erratic in performance so as to stop the loom unnecessarily. It is further important that the stop motion be effective as soon as possible after a break or other abnormal reduction in tension has occurred, otherwise defects in the weave will be produced in the meantime. Also it is desirable that the number of parts of the device which are required to move during normal operation, be kept to a minimum.

The invention aims primarily to provide a stop motion which will fulfill the above and other practical requirements met with in looms of the type above referred to, which requirements prior stop motions of which I am aware have failed in one or more respects to meet satisfactorily. Further objects and advantages of the invention will be in part obvious and in part specifically referred to in the description hereinafter contained, which taken in conjunction with the accompanying drawings discloses a preferred form of stop motion constructed to operate in accordance with the invention; the disclosure however should be considered merely as illustrative of the invention in its broader aspects. In the drawings:

Fig. 1 is a plan view with certain parts cut away and showing in simplified form, the main operating parts of a loom of the type above referred to, with which parts the invention is primarily concerned.

Fig. 2 is a simplified cross-sectional view showing a shuttle constructed in accordance with the invention, in operative relation to the immediately adjacent parts of such a loom.

Fig. 3 is an enlarged sectional view of the shuttle shown in Figs. 1 and 2, the section being taken parallel

2

to the plane of Fig. 1, and the parts being shown in positions assumed during normal operation.

Fig. 4 is a view similar to Fig. 3 but showing the parts in position to stop the machine.

5 Fig. 5 is a detail section on line 5—5 of Fig. 3 looking in the direction of the arrows.

In Figs. 1 and 2 I have shown the batten members 1 and 2 which should be understood as illustrative of battens used in looms of the type above referred to.

10 Carried by the battens are shuttle blocks 3 and 4, between which shuttles should be understood as mounted to move back and forth transversely of the machine in laying the filling thread or yarn, as is well understood in the art. Fig. 1 shows one such shuttle A engaging one of the shuttle blocks 4, and feeding the thread 5 which is to be woven into a narrow fabric strip 6, but it should be understood that a large number of such shuttles will normally be provided and located side by side across the machine, with each shuttle serving respectively one of a large number of fabric strips being simultaneously woven. It should be further understood that the batten members 1 and 2 and the shuttles carried thereby will be moved back and forth longitudinally of the strips in timed relation to the transverse movements of the shuttles as above referred to. The above main operating parts 1—4 of the machine and their mode of operation will not be described in further detail since various appropriate forms thereof have long been known and used in the art.

30 In accordance with the present invention each shuttle carries in the rear portion thereof, a contactor which is mounted to move between idle and active loom-stopping positions and which moves to its active position when the tension on the thread falls below the normal operating range.

35 The batten structure is provided with a target member past which the contactor sweeps during the above mentioned transverse movements of the shuttle. So long as the contactor is in idle position the target member is not affected thereby, but when the contactor is moved to active position by a drop in the tension as above referred to, transverse movement of the shuttle causes the contactor to activate the target member and the latter is appropriately coordinated with the loom driving mechanism to stop the machine. With the above relationship of loom-stopping parts, the stopping of the machine is not dependent upon the above mentioned forward and back movements of the shuttle, in other words the machine is stopped solely by the transverse shuttle movements above referred to, and therefore the motion stopping parts may be readily so coordinated that the machine will be stopped almost instantaneously, usually much more quickly than in the case of a stop motion which has to wait—so to speak—to come into operation until the occurrence of one of the above mentioned forward and back movements of the shuttle before coming into operation.

40 The shuttle A may be constructed for the most part as is conventional in the art, being shown as of D-like shape and provided with an appropriate quill 8 Fig. 3 from which the thread 5 is fed, and having an appropriate friction drag 9. From the quill 8 the thread passes first to a guide eyelet 10 shown as loosely carried by a mounting wire 11, and then successively through guide eyelets 12 and 13, and then out through a guide tube 14 mounted in the forward nose portion of the shuttle.

45 In the illustrated embodiment of the invention the contactor above referred to takes the form of a plunger 15 slidably mounted in the rear face portion of the shuttle and which when moved outwardly from the inactive position shown in Fig. 3, will activate the target member 16 (Fig. 2) when the contactor is moved into alignment with the target during the above mentioned transverse

movements of the shuttle. In Fig. 2 a target member 16 is shown in simplified manner, in the form of a plunger urged by spring 17 into the path of transverse movement of the contactor 15 when the latter is in active position, the plunger 16 being provided with a bridging switch member 18 which closes the circuit 19 when activated by the contactor 15. Appropriate circuit connections as known to those skilled in the art will be understood as provided in the circuit 19 to bring the machine to a stop under the above conditions.

An appropriate number of target members 16 etc. will be mounted in spaced relation along the batten structure, being carried for example by a bar 18a supported by brackets 18b extending from the batten member 2. Appropriate signal devices (not illustrated) such as are known in the art may be provided to indicate to the operator when the machine has stopped, which space in the loom needs attention.

Preferably the contactor 15 is positively moved between its idle and active positions, and positively held in each such position. In the form of the invention shown in Fig. 3, cam actuation is employed for this purpose, comprising a cam member 20 slidably mounted within the passage 20a in the rear portion of the shuttle. This cam member is provided with the inclined portions 21 which cooperate with the inclined walls of a slot 22 extending through the contactor 15. Fig. 3 shows the contactor in inactive position and movement of the cam member 20 to the right from the position shown in Fig. 3 to the position shown in Fig. 4, will move the contactor into the active position shown in Fig. 4. A stop 20b limits the movement of cam member 20 to the left as the parts appear in Fig. 3.

The cam member 20 is also connected to the eyelet 12 by a flexible tension member such as a length 24 of nylon cord guided by an idler pulley 25 mounted in the slot 20a. The eyelet 13 is urged by a spring 26 somewhat stronger than spring 23, toward the position shown in Fig. 4 wherein the eyelet 13 seats against the adjacent wall of the shuttle. Under these conditions the spring 23 moves the cam 20 into the active position shown in Fig. 4, eyelet 12 seating against the adjacent wall of the shuttle. Thus the contactor 15 is moved into and held in active position so long as abnormally low tension exists in yarn 5.

But when tension within the normal operating range is reestablished in yarn 5, spring 26 will be tensioned and this tension will be imparted to the cord 24, thus shifting cam 20 into the position shown in Fig. 3 wherein the contactor 15 is inactive. At times when the tension in yarn 5 varies within the normal operating range, the eyelet 13 may shift back and forth without however relieving the tension on cord 24 sufficiently to enable spring 23 to shift the contactor 15 to active position. The friction drag 9 is more powerful than spring 26, in other words when normal operating tension is being built up in yarn 5, eyelets 12 and 13 will move substantially into the positions shown in Fig. 3 before the tension becomes sufficient to feed the yarn from the shuttle, and spring 26 will have stretched sufficiently to insure that contactor 15 has been moved against the tension exerted by spring 23 into the inactive position shown in Fig. 3. It is only when the eyelet 13 moves out substantially to the position shown in Fig. 4, due to reduction in tension below the operating range, that the cam member 20 becomes sufficiently relieved of tension applied by cord 24, to enable spring 23 to move contactor 15 to active position. In other words, variations of tension within the normal operating range will not shift the cam sufficiently to move the contactor to active position.

By appropriate proportioning of the strength of springs 23 and 26 the device may be readily coordinated so as to be reliable in holding the contactor 15 inactive even under very slight operating tensions, and never-

theless be reliable in stopping the machine when the tension falls below the operating range. With the contactors carried by the rear portions of the shuttles and their targets carried by the adjacent batten structure, the stop motion does not have to await forward or back movements of the shuttles and may be set up to come into operation very quickly whenever a break occurs. During tension conditions within the normal range, the only part of the stop motion which moves to any substantial extent is the eyelet 13, which largely relieves the device of wear.

While the invention has been disclosed as carried out by the above described preferred embodiment thereof, it should be understood that changes may be made without departing from the invention in its broader aspects, within the scope of the appended claims.

What is claimed is:

1. In a loom of the character described, having batten and shuttle block structure and a plurality of shuttles mounted for longitudinal movement and for transverse movement with respect to the batten structure, mechanism for stopping the loom upon reduction in the filling yarn tension below the normal operating range, comprising a contactor carried by the shuttle, and having cam engaging means, a target member carried by the batten structure and positioned adjacent to the path of travel of the contactor during transverse movement thereof, an elongated cam member also carried by and slidably mounted in the shuttle in motion transmitting engagement with said contactor, and means responsive to changes in tension of the yarn being fed from the shuttle for actuating said cam member to move said contactor into position to activate said target member as the shuttle moves transversely, when the yarn tension drops below the normal operating range, and for actuating said cam member to move said contactor to inactive position when the yarn tension reaches a point within normal operating range.
2. A loom shuttle of the character described having a quill carried thereby, and a yarn guiding opening in the nose portion thereof, guide eyelets through which the yarn passes on its way from said quill to said opening, a contactor mounted in the rear portion of the shuttle for movement between active and inactive positions, a cam member also carried by the rear portion of the shuttle in motion transmitting relationship to said contactor, and means responsive to changes in tension in the yarn while passing through said eyelets for actuating said cam member to move said contactor between its aforesaid active and inactive positions.
3. A loom shuttle of the character described having a quill carried thereby, and a yarn guiding opening in the nose portion thereof, guide eyelets through which the yarn passes on its way from said quill to said opening, a contactor mounted in the rear portion of the shuttle for inward and outward movement with respect to the shuttle, a cam member also carried by the shuttle and engaging the contactor, the shuttle also carrying a spring urging said cam member to move in one direction, and a tension member acting between said cam member and one of said eyelets to urge said cam member to move in the opposite direction.
4. A loom shuttle of the character described having a quill carried thereby, and a yarn guiding opening in the nose portion thereof, guide eyelets through which the yarn passes on its way from said quill to said opening, a contactor mounted in the rear portion of the shuttle for movement between active and inactive positions, and means responsive to changes in tension in the yarn while passing through said eyelets for positively moving said contactor between its aforesaid active and inactive positions, said means comprising a cam member slidably related to said contactor and positively holding said contactor in each of said positions.

5. A loom shuttle of the character described having a quill carried thereby, and a yarn guiding opening in the nose portion thereof, guide eyelets through which the yarn passes on its way from said quill to said opening, a contactor mounted in the rear portion of the shuttle for inward and outward movement with respect to the shuttle, a cam member also carried by the shuttle and engaging the contactor, the shuttle also carrying a spring urging said cam member to move in one direction, and a tension member acting between said cam member and one of said eyelets to urge said cam member to move in the opposite direction, said shuttle also having a second tension spring means connected to another of said eyelets to apply tension to said tension member when the yarn tension is within the normal operating range.

6. A loom shuttle of the character described having a rear portion provided with shuttle block engaging parts, a nose portion provided with a yarn guiding opening, said shuttle also having a quill positioned between said rear and nose portions, said quill being spaced rearwardly of said nose portion, a contactor, means mounting said contactor at said rear portion of the shuttle for movements with respect to the shuttle between an inner inactive position and outer active position, means including a spring urging said contactor toward its outer active position, a yarn guiding eyelet disposed forwardly of said quill in position to move back and forth longitudinally of the quill in the space intervening between said quill and nose portion, and means whereby normal tension on the yarn passing through said eyelet and guide opening holds said contactor in its inner inactive position against the action of said spring, said last mentioned means including a tension member extending rearwardly from said eyelet and connected to said means including a spring.

7. A loom shuttle of the character described having a rear portion provided with shuttle block engaging parts, a nose portion provided with a yarn guiding opening, said shuttle also having a quill positioned between said rear and nose portions, said quill being spaced rearwardly of said nose portion, a contactor, means mounting said contactor at said rear portion of the shuttle for movements with respect to the shuttle between an inner inactive position and an outer active position, means including a spring urging said contactor toward its outer active position, a yarn guiding eyelet disposed forwardly of said quill in position to move back and forth longitudinally of the quill in the space intervening between said quill and nose portion, and means whereby normal tension on the yarn passing through said eyelet and guide opening holds said contactor in its inner inactive position against the action of said spring, said last mentioned means including a tension member extending rearwardly from said eyelet, and cam mechanism interposed between said tension member and contactor, said cam mechanism being contoured to move said contactor into active position and positively hold the contactor in such position, upon the release of normal tension of the yarn.

8. A loom shuttle of the character described having a rear portion provided with shuttle block engaging parts, a nose portion provided with a yarn guiding opening, said shuttle also having a quill positioned between said rear and nose portions, said quill being spaced rearwardly of said nose portion, a contactor, means mounting said contactor at said rear portion of the shuttle for movements with respect to the shuttle between an inner inactive position and an outer active position, means including a spring urging said contactor toward its outer active position, a yarn guiding eyelet disposed forwardly of said quill in position to move back and forth longitudinally of the quill in the space intervening between said quill and nose portion, and means whereby normal tension on the yarn passing through said eyelet and guide opening holds said contactor in its inner inactive position against the action of said spring, said last mentioned

means including a tension member extending rearwardly from said eyelet, and cam mechanism interposed between said tension member and contactor, said cam mechanism being contoured to hold said contactor positively in inactive position under different tensions on the yarn which are within the normal operating range of tension.

5 9. A loom shuttle of the character described having a quill carried thereby, a yarn guiding opening in the nose portion thereof, a contactor, means mounting said contactor on the shuttle for movements with respect to the shuttle between an inner inactive position and an outer active position, means including a spring urging said contactor toward its outer active position, yarn guiding eyelets interposed between said quill and nose portion, and means whereby normal tension on the yarn passing through said eyelets and guide opening holds said contactor in its inner inactive position against the action of said spring, said last mentioned means including a tension member interposed between one of said eyelets and said contactor, and a second spring connected to another of said eyelets to urge the latter to exert tension on said first mentioned eyelet under normal conditions of tension of the yarn passing through said eyelets and guide opening, and thereby hold said contactor in inactive position against the action of said first mentioned spring.

10 10. A loom shuttle of the character described having a rear portion provided with shuttle block engaging parts, a nose portion provided with a yarn guiding opening, said shuttle also having a quill positioned between said rear and nose portions, said quill being spaced rearwardly of said nose portion, a contactor, means mounting said contactor at said rear portion of the shuttle for movements with respect to the shuttle between an inner inactive position and an outer active position, means including a spring urging said contactor toward its outer active position, yarn guiding eyelets disposed forwardly of said quill in position to move back and forth from and toward each other longitudinally of the quill in the space intervening between said quill and nose portion, a cam member 30 slidably mounted in the rear portion of the shuttle in engagement with said contactor, a spring in said rear portion urging said cam member to move in one direction, means whereby normal tension on the yarn passing through said eyelets and guide openings holds said contactor in its inner inactive position against the action of said spring, said last mentioned means including a tension member connecting said cam member with one of said eyelets, and a second spring connected to another of said eyelets to cause said second spring to hold said contactor in inactive position during normal conditions of tension on the yarn passing through said eyelets and guide opening, and to relieve tension applied by said second spring to said cam member, to cause the latter to move said contactor to its outer active position under the action of said first mentioned spring, upon the release of tension on the yarn.

11 11. A loom shuttle of the character described having a rear portion provided with shuttle block engaging parts, a nose portion provided with a yarn guiding opening, said shuttle also having a quill positioned between said rear and nose portions, said quill being spaced rearwardly of said nose portion, a contactor, means mounting said contactor at said rear portion of the shuttle for sliding movements with respect to the shuttle between an inner inactive position and an outer active position, a cam member engaging said contactor, means mounting said cam member for movements back and forth along the rear portion of the shuttle, said cam member being contoured to hold said contactor positively in inactive position under different tensions on the yarn which are within the normal operating range of tension, and to move said contactor into active position and positively hold the contactor in such position upon release of normal tension of the yarn, a spring urging said cam member to move the contactor toward its outer active position, a plurality of

yarn guiding eyelets disposed forwardly of said quill in position to move back and forth longitudinally of the quill in the space intervening between said quill and said nose portion, a flexible tension member connected to one of said eyelets and extending rearwardly into connection with said cam member to apply tension thereto in opposition to said spring, and a second spring connected to another of said eyelets to urge the latter to move longitudinally of the quill in a direction away from said first mentioned eyelet.
